Inventor

UNITED STATES PATENT OFFICE

HERBERT LUTHER ADAMS, OF SOMERVILLE, MASSACHUSETTS

FLYING MACHINE

Application filed April 14, 1921. Serial No. 461,412.

My invention primarily relates to that class of flying-machines, which are heavier than air but certain details may be used on any flying-machine, air craft, or other uses.

5 An object of my invention is to provide means for increasing the vertical reaction or lift of the supporting surface with a decreased horizontal reaction or drag, common to supporting surfaces now generally used.

10 A further object is to provide movable wings that may be folded up, closed up, extended or unfolded in flight, or otherwise and if necessary to still further fold up or close up to enable the flying-machine to taxi

15 on the highway by the aid of special means to that end.

A still further object is to provide means for braking or means to reduce the speed on landing and means to increase the lift at

20 low starting speed.

A still further object is to provide better means of control of steering, of means to throw a machine out of a tail spin.

Another object is to provide means for increasing the tractive force of a given propeller or airscrew and decreasing the retarding effect by back pressure on the engine or body of machine.

The special means for taxiing on highway

30 may include means of steering on land that may be connected to means for steering in air and all operated by the same means. Independent means aside from the big motor may be used for taxiing and having mechanical connection to the wheels, said independent means may be used for cranking the big motor, operating the auxiliary apparatus, etc., said big motor may then be cranked in the air as well as on the ground.

40 The decreased drag above mentioned may to some extent become partly automatic by a flexibility of parts that adapt themselves to the condition.

A still further object is to provide an aerohydroplane that can rise from rough water at sea, by having extension vanes reaching into unbroken water while the flying-machine is in the air and not affected much by the waves.

50 A still further object is to provide extend-

able or withdrawable pontoons to reduce air resistance in flight, and safety and comfort on the water.

A still further object is to provide a propeller that has greater traction and less drag.

A still further object is to provide a terra-aerohydroplane, a machine that may be used universally on highways, land, water or open sea or ice and snow as well as in the air.

A still further object is to provide means as by using the brake on one side only to throw the machine out of a tail spin.

A still further object is to provide a wing joint and groove control: as a long cam touching at four corners and sliding in a wave shaped slot preferably on the opposite side of the joint from the wing tip. In this way a forward or backward movement by means of this cam gives at the same time a twisting movement to the tips. The cams or slots may

have means for being changed or moved, the joint may be a universal or ball and socket type, where the wing tips leave the wing in which their support lies they may have a piece of flexible rubber attached to both edges and meeting near the center of the opening or where desired, and stiff enough to be undisturbed by the velocity of the air in flight but flexible enough to allow the free movement of the wing tips, this is to stop objectionable air eddies, in this way a single line or if desired two lines may be used to give control or any desired means may be employed. A still further object is to provide either individual or collective movements of wing tips or both.

A still further object of the invention is to provide a parachute and means for supporting the same on an aeroplane in such a manner that the parachute will disengage the aviator from the aeroplane when the machine meets with an accident or the aviator may disengage himself.

A still further object is to provide a type of multiple parachutes that are arranged in tandem having means to haul them out of alignment as with a paravane chute to put one edge of each parachute in undisturbed air and means to control the inclination of the paravane chute.

A still further object is to provide connec-

tions of parachute to aeroplane that may be disconnected and attached to harness on aviators and passengers.

A still further object is to provide a spring actuated releasing mechanism having means to be manually and automatically operated.

A still further object is to provide a container for parachutes which has the automatic means for being forced and held open by the rush of air stream by it when restraining device is released.

A still further object is to provide a landing wheel so constructed that it will turn automatically when in use and still be resilient and have means for raising to a horizontal position for stream lining to reduce head resistance.

A still further object is to provide an aeroplane or glider that has automatic stabilizing means in its wing bearing surface and rudder, also certain other advantages which will hereinafter appear.

To these ends my invention consists in certain novel measures, which I will now proceed to describe and will then particularly point out in the claims.

In the accompanying drawings, Figure 1a is the main figure embodying many of the parts assembled with especial reference to the telescoping if desired. This telescope may have any means for drawing in or extending as lines and pulleys suitably arranged, or other means. This will enable with other features the quick and easy means for reducing width and length to allow storage in a small space or building.

Figure 1 is a part sectional plan of movable wing tips of the fan shaped type in this case attached to the end of an aeroplane wing.

Figure 2 is a modification of Figure 1 having extendable wing tip as does Figure 1 but a multiple pivot individual control type.

Figure 3 is a modification of Figure 1 of the telescopic multiple type and may have multiple or individual control or both. It is shown in the illustration with multiple control.

Figure 3a is a section of Figure 3 of the wing with the tips withdrawn.

Figure 4 is a modification of Figure 1 and Figure 3 lacking individual control but having end sealing device when closed.

Figure 4a is a section of Figure 4 of the wing showing the wing tip withdrawn.

Figure 5 is a modification of Figure 1 with a single pivot tip type.

Figure 6 is a modification of Figure 1a and Figure 3 of the telescopic single tip type.

Figure 6a is a section of the wing shown in Figure 6.

Figure 6b is a section of the wing in Figure 6 with the wing tip withdrawn.

Figure 7 is a modification of Figure 1 of the detachable or attachable single tip type.

Figure 7a is a part section of Figure 7 show-

ing the method of connecting the wing tips to the wing.

Figure 8 is a section of an aeroplane wing or of an aeroplane wing tip.

Figure 9 is an end view of an aeroplane wing with one type of wing tip set at one of the numerous angles possible.

Figure 10 is an end view of an aeroplane wing with wing tips set to conform to the shape of the wing.

Figure 10a is an end view of an aeroplane wing tip with movement of wing tips indicated.

Figure 11 is a perspective view and shows a method of control for wing tips that may be used by the aviator and located near him.

Figure 12 is a perspective view and shows one means of rotating the separate parts of the wing or wing tips.

Figure 13 is a modification of a movable wing that may be folded up or extended in flight, or otherwise to furnish an aeroplane that may taxi on the highway.

Figure 14 is a rear view of Figure 13 and shows one method of connecting the various parts of the same.

Figure 15 is a detail of a section through a wing tip or similar construction showing a method of connection as for Figure 13 or other similar figures.

Figure 16 is a detail of the lower half of a connection joint as in plan of Figure 15.

Figure 17 shows a detail of how the belts on the pulleys of Figure 12 may be secured to prevent slipping.

Figure 18 is another view of Figure 17 with pulleys rotated as they may be in use.

Figure 19 is a detail of the levers shown in Figure 11 and may be used for any operation desired.

Figure 20 shows a master lever for rotating a shaft on which other levers have been set.

Figure 21 shows how a line control to a pulley may be secured to prevent slipping with especially reference to Figures 12 and 41 or any place desired.

Figure 22 shows a method of laying thin layers of material together preferably wood with cross section lines going into the direction of the grain.

Figure 23 is a plan in part section showing modification of Figure 13 others showing multiple extension wing.

Figures 24, 25 and 26 are modifications of Figure 22 showing means of combining thin layers of material as in Figures 22 or 28 to meet the stresses of each individual case at any point in the structure.

Figure 27 shows an edge view of how the various thickness of material may be stopped to meet the stresses at any points desired so that it may be uniformly rigid or may have a little flexibility.

Figure 28 is a view of the bottom of Figure 27 to show that the line marking the

change in thickness may have any shape to fit the stresses at different points.

Figure 29 is a modification at a most desirable position of multiple tip of wing tips.

Figure 30 is a modification of a part of the control shown in Figure 13.

Figure 31 is a modification of a wing tip (see Figure 8) or a part of a wing having a flexible lower edge to act as a pressure equalizer and shock absorber. This may be used as a single wing or blade, etc., or in any multiple shape or with any form in any number of wings.

Figure 32 is a modification of Figures 8, 10 and 31, etc., showing wing parts fitted to reduce air resistance.

Figure 33 is a modification of Figure 36 and shows a means of attaching the controls to this type of steering rudder.

Figure 34 is a view of an aeroplane showing means for folding the wings slightly back on one and forward on the other to aid in steering and also showing how the wings may be folded back to reduce the width so that it may avoid any obstructions on landing, etc., or in taxiing on the highways.

Figure 35 is a view of a part of Figure 32 showing the flexure of the lower edge.

Figure 36 shows a four sided rudder with means for attaching a joint at or near the center of gravity so that it may be moved if desired, to direct the aeroplane.

Figure 37 is a diagrammatic view of framing of Figure 34 using edges of a triangular pyramid like means of framing.

Figure 37a shows rear view of Figure 37.

Figure 38 is a rear view of framing of Figure 37 with two rear skid sticks at inclined angles to aid in steering or stopping the machine as each may be operated independently of the other.

Figure 39 is a side view of a part of Figures 37 and 38.

Figure 40 is a plan showing the same idea applied to elevating rudder as in Figure 47.

Figure 41 is a modification of Figure 39 as a means of steering while taxiing or otherwise.

Figure 42 shows a front view of an aeroplane with wing gradually decreased in thickness or strength and having flexure at end to equalize pressure and give ease and lightness.

Figure 43 shows a means of operating mechanically by aid of air, etc., the control of any part of the machine action desired.

Figures 44 and 45 are modifications of Figure 36.

Figure 46 shows a means of connecting rudder in the air to a steering rear wheel for directing the machine on land and both may be connected to the same shaft.

Figure 47 shows how the steering apparatus may have means for reducing the strain of turning in the air.

Figure 48 shows means for connecting lines of Figure 41, etc., to main steering lines.

Figure 49 is a modification of Figures 8 and 35, etc., showing means for top and bottom edges being flexible.

Figures 50 and 51 are modifications of Figure 48.

Figure 52 is a perspective view of a modification of a part of Figure 36 using a shutter to control elevation and lowering of aircraft.

Figure 53 is a rear view of complete shutter control device for steering on land and in the air.

Figure 54 is a plan that shows how Figure 1 may be placed and used as a part of the steering mechanism.

Figure 55 is a side view showing how these parts in Figure 54 may be used as an elevating or depressing rudder.

Figure 56 is a view of framing showing how a spring may be used as a shock absorber when dropping into an air pocket, etc.

Figure 57 is a section of the lower part of tension member of Figure 56 when flying, in which the spring is located to give play to the wings when meeting various stresses.

Figure 58 is a perspective view of a connection on the bottom strut or longerons of fuselage to which the tension members may be detachably connected.

Figure 59 is a perspective view of an aeroplane fuselage and wings showing the wings folded up and having means to hold them up and the tips folded back as for storage or for taxiing on the highway.

Figure 60 is a perspective view of pin for connection shown in Figures 58 and 62.

Figure 61 is a perspective view of modification of Figure 37 in which the three struts framing is modified to meet conditions in which the load does not meet at a point.

Figure 62 is a perspective view of a modification of Figure 58.

Figure 63 is a perspective view of a modification of Figure 61.

Figure 64 is a view showing a means for movement of wing or wings in two directions or planes.

Figure 65 is a view of a hand lever and movement on a uniform joint and having means for stopping and being fixed in points other than a straight line or one plane. Figure 19 or 43 may be combined with this view in any way desired.

Figure 66 is a perspective drawing showing a wing but in which a wing tip may move showing means for closing the back edge of the opening when flying with wing extended.

Figure 67 is a view of fastening means comprising holes and grooves shown in Figure 68 for which levers 65 may be moved.

Figure 68 is a view or modification of end of tip shown in Figure 65.

Figure 69 is a modification of Figure 67.

Figure 70 is a section of what Figure 67 or Figure 69 may be like.

Figure 71 is a modification of Figure 5 having means added to close the remainder of opening shown in Figure 66.

Figure 72 is a perspective view of two levers of Figure 19 type attached to any part of Figure 65 or elsewhere for operating two or more wings like Figure 64 or 73, etc.

10 Figure 73 is a modification of Figures 5, 10 and 64.

Figure 74 is a perspective view of a device to go with Figure 59 for raising wings.

Figure 75 is a cross section of Figure 76

15 and having means for closing the multiple opening in the plane tip or section with one or more curtains.

Figure 76 is a perspective view of a part detail plan of Figure 75.

20 Figure 77 is a longitudinal section of hinged elastic curved extending wing tip with flexible point.

Figure 78 is a modification of Figures 3 and 23.

25 Figure 79 is a section of one method of reducing noises by attaching soft, fluffy fibers at edge that cause whistling and other noise. It may or may not be adjustable, as shown adjustable in this case, to find the minimum 30 length or exposed fibers necessary, to produce desired result.

Figure 79a is a cross section through Figure 79.

35 Figure 80 is a modification of Figure 56 with a compression spring in place of tension spring flexible wing.

Figure 81 is a section detail of a pivot or ball and socket joint and tail rudder or for use wherever desired.

40 Figure 82 shows how the wings in Figure 80 may be folded up.

Figure 83 shows a method of connecting power to closing or folding landing wheel and using a space rod for transmission to the 45 other wheel if desired or both may have separate connections.

Figure 84 shows a modification of withdrawable or extendable wings of the wedge type using means of shifting one plane relative to the other or other means. This idea 50 may be made in any form desired.

Figure 85 is a view of hydroplane with stem and slide for stem and extension slide are shown in section showing the pawl and the lines used in control, the line connected to the pawl is so arranged that a pull will disengage the pawl, the other lines attached to the extension slides may then vary the angle 60 of the vanes.

Figure 86 is an extended view of Figure 84.

Figure 87 is a modification of the extendable wing idea and may have control similar to Figure 6 or other means and may have

releasable pockets on the under side to aid in braking effect.

Figure 87a is an end view of Figure 87.

Figure 88 is a section through the hub of the main propeller showing how an auxiliary 70 propeller may be detachably connected.

Figure 88a is a part section showing how the auxiliary blades may be made a part of the main propeller hub.

Figure 89 shows how auxiliary resistance 75 may be hauled out of concealment and held as shown for breaking speed when landing, etc.

Figure 90 is a plan view of Figure 88.

Figure 90a is a side view of a modification 80 of Figure 90.

Figure 90b is a side view of a modification of Figure 90.

Figure 90c is a front view of a modification of Figure 90.

Figure 91 shows a method of supporting and arranging the engine to give maximum clearance of propeller and also shows the means attaching landing wheels and a section of the stream line container in which landing 90 wheels may be encased in flight, also a section of auxiliary floating means as gas or air bags drawn out and held in place by lines.

Figure 92 is a modification of the idea in Figures 88 and 90 to draw the air away from the center and throw it towards the side and compress it into a torus with a somewhat wedge edge section giving a more concentrated and intense pressure and furnishing greater tractive effort for power expended.

Figure 93 is a section of a collapsible pontoon enclosed with stream line container and hydroplane vanes for take off on the water they may be withdrawable as shown in one of them or both may be like Figure 85 a power connected air pump and air tank with piping and valves for inflating and deflating the main and the two side pontoons also the landing wheels are enclosed in stream line container.

Figure 94 is a closing container for landing means on land but may be used in principle for enclosing the take off means from water.

Figure 95 is a side elevation of a modification of Figure 93 rigid tank with telescope extension struts to let or force the tank down and means for taking the horizontal thrust and means for reducing the friction on advancing in the water.

Figure 96 is a modification of Figures 93 and 95 with a collapsible pontoon.

Figure 97 is a detail of a part of air or hydraulic telescoping hydroplane vanes extending device or automatic stabilizer for rough water. An air chamber in hydraulic pipe line or any other means may be added to give greater stability, also if it is desired to enclose the vanes means may be provided for automatically turning them 90° by corruga-

tion on the outside of each section in such direction as desired, and a similar female groove through which they are held preferably straight but they may have a curve to turn the vanes by at right angles before entering the stream line receptacle. The water may be put into the system just before the take off and discharged when in flight to reduce the weight, if air is used it may be kept on or off all the time as the case may be. When the water is out the means for closing the container and keeping it closed may hold the vanes in place without other means, if desired the outer case may be wholly enclosed in the body of the flying machine to which it is attached.

Figure 98 is a perspective section of a modification of Figure 12 having a ball and socket and a four point cam in wave like groove inside a spherical segment. This segment may be moved to give a varied curve having a line for moving segment through cleats.

Figure 99 is a view of cam and groove spoken of in Figure 98. This gives a rotary wave like motion to wing tips when lines 1 and 2 are moved.

Figure 100 is a detail section of the rudder ball bearing showing the means for shifting the center of gravity.

Figure 101 is a diagrammatic representation of the construction of hollow crank shaft 63 and means for pitch on changing the inclination of auxiliary propeller; also the method of supplying fresh liquid if leaks develop without stopping the engine.

Figure 101a is an enlarged horizontal sectional view of auxiliary propellers shown in Figure 101 showing the method of changing the pitch and angle of same.

Figure 101b is a cross section of the propeller adjustment means shown in Figure 101.

Figure 101c is a cross section of the rear end of the crank shaft.

Figure 102 is a view of a modification of rear wing tips 75 that have flexible edges.

Figure 102a is a rear view of Figure 102.

Figure 102b is a detail of the rear wing tips shown in Figure 102 and 102a.

Figure 103 is a longitudinal cross section of device for launching aircraft having a detachable connection to aircraft for developing high speed at starting point and having an anchor and trigger for holding the machine and aircraft with propeller in full action and for changing cylinder to give initial impetus where on the trigger may be released by the aviator or the attendant when ready to start. In this way, the aeroplane may leave high buildings, ships at sea, small fields, etc.

Figure 103a is a longitudinal cross section of device for launching aircraft and is a modification of Figure 103 in which special explosive charges may be used.

Figure 104 is a view of a manual means for

extending strut 10 to wings to allow angle to the horizontal or to reduce said angle.

Figure 105 is a front view of a biplane with top plane divided detachably in the middle so that each half may be moving singly in opposite direction or in the same direction for banking and steering.

Figure 105a shows a stream line single strut frame between planes of the double cross wire section that may or may not be adjustable, 75 preferably not. This is to reduce air resistance common to wires and to prevent side slip.

Figure 105b shows a plan of a strut with a mid section in the same type which may be used for the struts between planes with holes through which the wire may pass. This strut shall preferably be hollow but may be solid if desired.

Figure 106 shows a giant liner with multiple wings attached to adjustable frame and the frame attached to a pivot near the center of gravity to rotate so that the angle of incidence may be changed without changing the angle of body which may run on an even keel. The paying out of lines connected to the forward end of plane with the rear end of adjacent frame and the hauling in on both inclination lines will alter the angle or the reverse of this principle may be used to tilt said multiple wing flattened and make one big plane.

Figure 106a is a view of the same general type with a pivot shown above the body to give greater movement.

Figure 106b is similar to 106a in a different position.

Figure 107 is a view of a connecting line for paravane type parachute used either for one or more passengers or for the aeroplane.

Figure 108 is a view showing a means of controlling a string of standard type parachutes in tandem having auxiliary standard type chute to act as a paravane to throw them out of one line to put one edge of chute in undisturbed air and means to control inclination of paravane chute.

Figure 108a is a view showing the means for controlling a string of standard type parachutes in tandem uncontrolled by the paravane chute which may be used to act as a pilot chute in drawing the others from the container.

Figure 109 is a diagrammatic view showing the effect of auxiliary propeller upon the wake of the air keeping away from the fuselage.

Figure 109a is a diagrammatic view of propeller and auxiliary propeller showing how the propeller directs the air from the center outward and how the curved outer blades tend to direct air without the diameter of the propeller within to give greater pressure to afford greater tractive force.

Figure 110 is a perspective view of a self

stabilizing aeroplane with resilient retractable landing wheels and a self stabilizing rudder on a universal joint. This plane may be used as a glider or may have motive power added without departing from the essential features involved.

Figure 111 is a cross sectional view of Figure 110 showing the spring action of the automatic steering retractable landing gear with means shown for controlling the rear edge of aeroplane wings to aid in steering. This steering means may be employed in such places as found desirable.

Figure 11c is a diagrammatic perspective view of an aeroplane showing one form of a location of releasing device and container for parachute.

Figure 2c is a sectional view of spring actuated automatic releasing device with manual control of said automatic means.

Figure 3c is a detail of the universal joint shown in Figure 2c furnishing means for operating device automatically.

Figure 4c shows a reinforced garment with means for attaching the parachute to the body of the aviator.

Figure 5c shows the releasing cover to the container of the parachutes or air anchors with releasing device for said cover.

Figure 6c shows the cover released.

Figure 7c is a detail of pin releasing device.

Figures 8c, 9c, and 10c shows a method of folding the parachute on top of the plane but any approved method of folding parachute may be employed, preferably that used by the present standard chutes.

Figure 11c shows a front view of releasing mechanism with pins released which can be performed manually without the aid of the automatic device.

Figure 12c shows a spring for removing a part of cover to air anchors automatically when cover has been released.

Figure 13c shows a means of attaching parachute to aviator to give the greatest freedom of movement to aviator.

Figure 14c is a detail of means for attaching shroud lines to harness on aviator.

Figure 15c is a front view of protecting means for the head of the aviator.

Figure 16c is a plan view of Figure 15c or a modification thereof.

Figure 17c is a side view of Figure 15c.

Figure 18c is a diagrammatic view of automatic releasing mechanism.

Figure 19c is a front view of a protector for connecting lines to parachute where it enters the container.

Figure 20c is a plan of Figure 19c.

Figure 1d is a perspective view of one form of my life preserver in repose.

Figure 2d is an enlarged rear view of one means of securing the attaching means of the parachute to the aviator to inconvenience

the movements in control of the airship as little as possible.

Figure 3d is an enlarged perspective view of the automatic parachute releasing means shown in Figure 1d.

Figure 4d is an enlarged perspective view of the lever for restraining the automatic releasing means shown in Figure 1d.

Figure 5d is an enlarged top plan view of parachute held in position on the aeroplane.

In illustrating this device more specifically an opening wire 1, and if needed a closing wire 2 is one of the simpler forms of operating wing tips 3 in the smaller sizes, any other means as a long shaft and worm gearing may be used in the larger sizes with hand or mechanical operation. These wing tips

3 may have one or more means of movement, or divisions, designated 3' 3" 3'" etc. or 3a, 3b, 3c, etc., and may have the same or similar means of operating as wing tips 3 have, or any means found desirable. Pivots 4 about

which wing tips 3 move; to take some of the strain off bearing 4 clip 5 which travels in circular groove 6 and roller bearing 7 for

making it easier to turn tip 3 or 3a, 3b etc., grooved pulley 8 eccentric or concentric with bearing 4, and having lines 1 and 2 attached by screw 9. A similar means may be

used for connecting the other ends of lines 1 and 2, or if one more line is used line 1 etc. near the operator. I choose to illustrate the

means of operating by use of lines because of the simplicity in illustrating, nevertheless realizing that it may not be done in that manner, for any known or unknown method

found desirable may be used in the operation of the wing tips. The object to be accomplished can be performed by one skilled in

the art when once the general principle is disclosed as by lines and levers with guides

and pulleys, etc., these being easily translated into other means of power transference by skilled mechanic or designer in this line of

work.

The various lines 1 and 2 from the various wing tips 3 may be combined and extend to a lever or they all may extend to an independent lever 78 like these shown in Figs.

11 and 19, etc., and attached to a jack shaft 79 having a master control lever 80, as shown in Figs. 11 and 20. Each wing tip can be operated or be attached to an adjustable lever

78 on the shaft 79 which when all have been set they can be operated by a master lever 80 or by several master control levers 80 that is

secured from turning except as desired by releasable ratchet 81 attached to sprocket 82 that can be attached by screws 87 to one sta-

tionary object 83 to hold all parts in the system where desired. The levers 78 can have ratchet 81 operated by extension 84 to a grip

85 of lever 78 in the customary manner. These auxiliary sprockets 86 have keys 88

securing them to shaft 79. Lever 80 can be

70

80

85

95

100

105

110

115

120

125

130

secured by key 89 to shaft 79. Combined these figures are a disclosure of a method of fine shades of separate, independent or individual and collective controls.

- 5 Lines 1 and 2 and all other lines can of course have all desired guides, shafts 92, 93, 96, 98, etc., and pulleys 90, 91, 95, 96, etc., to direct said lines where desired as indicated partly in Figs. 12, 65, 67, 69, 70 and 72, etc., 10 Fig. 43 is used to indicate the application of power to operate any of the levers, and shows the arc or cam 8a on which lines 1 and 2 and others may be carried if the movement is far enough to warrant it. This arc 8a may 15 extend all the way around and from a drum or spiral on which the line is wound by a motor or geared connection with clutches to throw the various parts in or out of operation (as above) that may each have separate clutch 20 connection to power on a counter-shaft. The line 1 may be with line 2 on a winch like drum 8a or they may practically have two drums or separate places on the same drum where one is wound up as the other is payed out. 25 The ends or the center may be securely attached to the drum. Combined these figures are a disclosure of a method of fine shades of 30 separate, independent or individual and collective control. Some of the lines may be slacker than the other tips adjacent so the power to move can be put to starting one at a time, the slackest one starting last. This can be accomplished without external connection or the teeth in the sprocket may be of 35 varying sizes to produce the same effect as slackness in the lines or any one of a number of methods may be used to produce any collective movement desired. A spiral arrangement of lines set at different angles of starting to increase in size, for instance, is another way.

In this division for the purpose of definitely disclosing the ideas in the drawings and specification, the following Figures 1, 1a, (1b, 45 2b) 2 to 32 inclusive 34, 35, 37, 38, 40, 42, 43, 46, to 80 inclusive, 82, 84, 86, 87, 89, 98, 99, 102, 105, 106, and the subject manner in the specifications related thereto are all a part of this division but may be used without prejudice 50 in connection with other divisions. If anything has been overlooked in this division the right to insert it later is reserved.

Figures 11, 19, 20, 43, 65, 67, 68, 69, 70 and 72 disclose individual independent and multiple or collective control of any part desired.

Figures 10 and 29 show more clearly than Fig. 9 the principle referred to for Fig. 9 is as it says "one position," but not the main one. The principle was obtained from observation of the motionless flight of buzzards through field glasses in or about 1915.

It is intended if desired to correct Figs. 1 to 4 to such means of control as are referred to in Figs. 11, 43, 65, 67, etc., Figs. 2, 64, 98 65 show individual or independent lines to ex-

tend wing tips independently or collectively in a system which may or may not move together in unison, for the location of lines on the lever or the size of the drums, cams, etc., will determine the relative movement of one tip to another one adjacent to it or if the line to one is made slack than the other the slackest one would start to move last. This method makes starting easier than if they all move together in unison. Any sort of a spiral place for lines winding on or off the shafting may cause different tips on the same end or edge of wing to move differently. The bottom end of pivot 4 may have attached means to which may be attached a fixed or a detachable tension member 10, that may also take a part of the load of the wings when not in flight, if desired. The lower part or any part may have an adjustable retained spring 11. The means for retaining spring 11 in case of undue strain or rupture is pin 12 working in slot 13. In outer casing 14 both ends of tension member 10 may terminate in an eye connection 15, which may be held detachably connected by bolt 16 to an eye connection 17 that may be attached to keel or lower part of fuselage as member 18, which combined with two other members 18a form the main connection or support for the rudder 19 which may have a pivot passing through, or near the centre of gravity 20, or as desired. In all cases numerals with letters, etc. following them shall be regarded as modifications of the number, if not otherwise stated, or some slight change. The rudder 19 may be controlled by lines 21 and 21a and 22 and 22a. To lines 21 and 21a may be attached lines 23 which are control steering lines 23 to steering rear landing means 24 so that the same steering means act in air, on land, or on water, wheel 24b is an air tight tank, disk, pneumatic, tired. Wheel 24b, lines 23 may pass around a grooved pulley 8d, (also see Fig. 21 for plan) attached to forked shaft wheel. Modification of steering gear 19d is intended to act as a pneumatic brake, if desired, by closing tight the shutters composing the device, brake 25 may be used to break landing device 24 a pneumatic tired wheel. A line 26 and a spring 27 are operating means for brake 25 which moves on a pivot, or bearing, until it is brought to bear forceably on the tire of the wheel 24, according to the pressure exerted by line 26.

In steering a variable control with holes 28 and pin 29 for fitting in any hole 28, desired, pin 29 is raised by trigger 30 and forced down by a spring, a swivel 31, or ball and socket joint furnish a flexibility of movement of lever 32. Leading to said holes 28 may be 125 grooves for guiding point 29 from one said hole 28 to another, lever 32 may have various lines attached to it in various ways to control the withdrawing or extending of wing tips 3 and rudder 19 etc. Line 33 for mov-

ing the wind stop 34 may be movable or have means of being moved, as desired. The line 35 is for shifting the center of gravity of steering means. The cam 36 slides in a movable groove for controlling movable wing tips. 5 There is means for controlling movement 37 of landing wheel forks or bearing members. The lever 38 is for closing cover to stream line container of landing or take off mechanism, etc. The joint in the main supporting surface or main hinge 39 near the body of the machine is in a general direction of flight.

Pocket like parts 40 are provided having a line 41 to hold them extended, and a brace 42 to hold the shape, and a pulley 43 to control pocket 40, by means of line 41. A hydroplane 44 attached to stem 45 having a head 46 to which a paul 47 may be attached preferably centrally the paul 47 engaging the rack on the side of the slide 48, the paul 47 having a line 49 attached so that a pull on the line will release the paul 47 from rack, and further pulling may lift the stem 45 in slide 48, 15 lines 50 and 50a are connected to opposite ends of the head 46 and paul 47 when engaged in rack may act as a fulcrum to change the angle of incidence of the hydroplane within limits as desired, a brace may be let in or out as desired. The breaking means 40 or other special air scoops may be used to force air into a receiver 51 for filling pontoons 52 or a pump cylinder 53 properly connected to power may be used to fill receiver 51, 20 valves 54 in piping being placed as desired to control the air entering the pontoons 52 and 52a and separate valves 55 may be provided to release the air from the pontoons 52. The pontoons 52 may be reinforced by lines 25 56 these lines may separate from or be a part of the means for hauling in 51 and out 58 of receptacle 59 of pontoon when withdrawn. A cover and protector 60 with brace 61 has means for being controlled. The propeller 62 may have a threaded hole on the end of the shaft 63 to which is attached an auxiliary shaft 63a on which is a double beveled propeller 62a to change the direction of air. The shaft 62 to engine XX bears 30 on a frame 65 the frame 65 has lugs 66 that are close to shaft 62 or near the line, the lugs 66 are to rest on the upper part of the frame 18a. The runners 67 may be detachable if desired. The upward bevel bat 35 fins 68 to rudder 19e are to give added stability and poise to the guiding. The cover 69 extends to stream line container 70 for landing gear. The adjustable diagonal brace or line 71 to take the horizontal reaction, of 40 extendable pontoon 52d is protected by door 60b and resting on platform 73. The adjustable brace 72 as provided for hydroplanes 44 and to take their horizontal reaction. The line 74 is to afford means for holding wings 45 3a when brace 10 has been released. The

rear wing tips 75 extendable in the general direction of the line of flight. A forwardly inclined lug 76 is made to engage in part of said machine and to be thereby detachably connected to said machine. Trigger 77 is to hold said machine in place until in readiness to be released with a flying start. 70

According to the accompanying drawings 8 denotes the lower plane of an aeroplane, 75 102 the upper plane thereof which is connected to the lower plane by means of uprights 103. The aviator sits on the lower plane and a suitable footrest 104 is provided for his convenience. 75

The numeral 105 indicates a jacket or other supporting device having reinforcing strips 106 which pass under the armpits and return to the rings 107 which are on top of each shoulder or other convenient place. In ring 107 are hooks α or other means which may be used to attach or detach the rest of the apparatus from the body. 80

The supporting ropes or strips 108 pass down the back of the aviator under the belt and up to the parachute 109 reposed in the upper plane of the aeroplane. One method of constructing the automatic device for automatically releasing the parachute is to use a weight 110 suspended by a universal joint 111, the end of the weight above the joint having a ball 115 working in the dished socket 116 which is of sufficient size to cover the ball as long as the aeroplane does not tip beyond control of the aviator, but when the ball gets outside of the said dished socket, 90

the spring 117 operating upon the shaft 118 forces the dished socket downwards, drawing the rod 118 likewise downwards through the supporting joints 119. The wires 120 are connected to the rod 118 and they are therefore drawn downwards over the pulleys 121, pulling out the pins 122 from their fittings 123 and eyes 124 of the parachute or cover. The pins 122 are normally held in engagement by the springs 125. When the pins are pulled out the strip 126, which is used to keep air from under the parachute when the same is not to be used, is released from similar retaining members, and the parachute immediately begins to take air and said parachute leaves the top of the flying machine, drawing the aviator with it by means of the ropes 108. A hinge or other means 127 serves to hold the strip 126 in position. 105

A brace 112 serves to hold the universal joint 111 in position. 112 is held by means of the screws or bolts 113 to the frame or uprights 114 attached to the member 102. 110

A lever 128 operating on a bracket 129 serves to grip the arm of the weight 110 to prevent the weight from moving to release the parachute 109. The arm is held in restraint by the three piece member 130 having a gap, closure of the same being had by means of the rod 103 normally held in place by the 115 120 125 130

spring 132 operated by the handle 133. When the aviator wishes to try a dangerous dip he merely reaches for this lever which is close by, swings it on its pivot and works 5 the handle 133.

A belt 134 with snap catch 135 serves means to hold the ropes 106 tight to the back of the aviator to keep them in a convenient position when not in use.

10 It is clearly obvious that those skilled in the art may vary the details of the construction and combinations of parts without departing from the spirit of my invention and therefore:—

15 I have shown an apparatus embodying my invention in several general forms but do not wish to be understood as limiting myself strictly to the precise details of construction hereinbefore described. I do not wish to be 20 held to exact shapes or dimensions or to any particular combination of parts but wish to be free to use any part herein shown or described or covered by the claims with any other part or parts whether shown herein or 25 elsewhere.

In illustrating this device more specifically in the accompanying drawings the horizontal wing surface 201 has a diagonal extension surface 202 which may or may not be 20 adjustable diagonally by suitable wire framing. The forward edge 203 of said wing surface is curved and has framing concealed within the wing as at 204 which is attached to struts 205 constituting the frame work of 25 the wing surface. The wire ropes 208 are attached to a lever arm 209 pivoted on struts 205 and connected to the rear part of wing surface 201 to warp said surface or rotate it about its connection at 204. A rear landing wheel 206 has sprocket 207 pivoted through a brace 210 attached to longerons 211 and are attached to the framing of wing surface and converge back to a central point 212 which is a universal joint connection to rudder 40 with self stabilizing surface 213 attached to the main body of the rudder 214 held in place by framing members 215. Lines 216 are attached to rudder surface 214 or extendable within control of the operator for directing 45 the control of rudder surface 214 and 213. At the lower end of two of the struts 205 is attached a hinged socket 217 that can go fore and aft in hinge 218. The lower part of 50 socket 217 has a keyed spindle 219 with a pin joint in which sprocket 220 is attached. In the sprocket 220 a pneumatic tired wheel is placed. The upper end of sprocket 220 has an arm that extends up to a point near joint 218 to which is connected a spring 222 making it possible to take up slight shocks of 55 the aeroplane in landing or take off. This arrangement provides for the wheels turning automatically when under stress of forward movement and still be resilient. A stop 223 60 is attached to the upper part of sprocket 220

that has a stop arrangement at socket 217. A leaf spring 224 is attached to the rear part of wing framing to take the main shock of landing wheels. A line or similar arrangement connects to the tip of leaf spring 224 70 and is attached to framing 205 near joint 218 to keep the tip of spring in the correct position when wheel 221 is forced back or drawn up. The socket 217 has a connection to a brace 225 connected with a joint strut 205 to keep wheel 221 in position desired while swinging back and forth. A line 226 is attached to the extension to sprocket 220 for raising wheels to a horizontal position for stream lining to reduce head resistance. The rear wheel 206 may be constructed to turn automatically or may have lines for directing its control, or may be operated by lines attached to lines 216 for controlling the horizontal steering of rudder. 80

Having thus described my invention, what I claim as new, and desire to secure by Letters Patent, is—

1. In a flying machine of the type having independent and collective controlled wing tips comprising openings that have a general line of direction from above the plane to below the plane with the said line above the plane being in advance, relative to the direction of flight of the said line below with individual and collective control of tips (in groups and) for closing or opening, openings for parts that are not movable. 90

2. In an aircraft, the combination with the main supporting wing surface on each side of the aircraft of auxiliary surfaces mounted to move both forward and aft, and laterally, of a master lever or joy stick securely attached to a shaft with means of securing in any position and having a multiplicity of levers connected to auxiliary surface and rotating on said shaft securable to sprockets that are secured to said shaft. 100

3. In an aircraft, the combination with the main supporting wing surface on each side of the aircraft of auxiliary surface mounted to move both forward and aft, and laterally of a master lever or joy stick securely attached to a shaft, with means of securing in any position and having a multiplicity of levers connected to auxiliary surface and rotating on said shaft securable to sprockets that are secured to said shaft, and said auxiliary surface mounted to rotate. 110

4. In an aircraft, the combination with the main supporting wing surface on each side of the aircraft of auxiliary surface mounted to move both forward and aft, and laterally of a master lever or joy stick securely attached to a shaft, with means of securing in any position and having a multiplicity of levers connected to auxiliary surface and rotating on said shaft securable to sprockets that are secured to said shaft, and said auxil- 120

iary surface mounted to rotate by movement of said surface.

5. In an aircraft, the combination with the main supporting wing surface on each side of the aircraft of auxiliary surface mounted to move both forward and aft, and laterally of a master lever or joy stick securely attached to a shaft, with means of securing in any position and having a multiplicity of levers connected to auxiliary surface and rotating on said shaft securable to sprockets that are secured to said shaft, and said auxiliary surface mounted to rotate by movement of said surface laterally.

15 6. In an aircraft, the combination with the main supporting wing surface on each side of the aircraft of auxiliary surface mounted to move both forward and aft, and laterally of a master lever or joy stick securely attached to a shaft with means of securing in any position and having a multiplicity of levers connected to auxiliary surfaces and rotating on said shaft securable to sprockets that are secured to said shaft and said auxiliary surface mounted to rotate by movement of said surface a part of which is secured in a curved mounting.

7. In a flying machine, wings on opposite sides of said machine, each of said wings provided with a series of adjustable adjacent wing tips and means for independently or collectively controlling the tips of each series for varying the air flow between adjacent tips.

25 8. In a flying machine, wing portions on opposite sides of said machine, an aileron on each of said wing portions, means for independently or collectively controlling said ailerons, and means providing a yieldable cantilever attachment for each of said portions to said machine.

9. In a flying machine, wing portions on opposite sides of said machine, an aileron on each of said wing portions, means for independently or collectively controlling said ailerons, means providing a cantilever attachment for each of said portions to said machine, and means for yieldingly transmitting shocks from said portions to said machine.

10. In a flying machine, wing portions on opposite sides of said machine, a series of adjustable, adjacent wing tips on each of said portions, each said tip being rotatable about a longitudinal axis thereof to provide a control for airflow between adjacent tips, and means for independently or collectively rotating the tips of each series.

11. In a flying machine, wing portions on opposite sides of said machine, a series of adjustable, adjacent wing tips on each of said portions, each said tip being rotatable about a longitudinal axis thereof to provide a control for airflow between adjacent tips, means for independently or collectively rotating the

tips of each series, said means for rotating said tips being mounted within the wing portions in concealed position.

12. In a flying machine, wing portions on opposite sides of said machine, a series of adjustable, adjacent wing tips on each of said portions, each said tip being rotatable about a longitudinal axis thereof to provide a control for airflow between adjacent tips, means for independently or collectively rotating the tips of each series, and means for adjustably supporting each of said wing portions permitting folding thereof toward the body of said machine.

13. In a flying machine, wing portions on opposite sides of said machine, a series of adjustable, adjacent wing tips on each of said portions, each said tip being rotatable about a longitudinal axis thereof, and means for independently or collectively rotating the tips of each series.

14. In a flying machine, wing portions on opposite sides of said machine, a series of adjustable, adjacent wing tips on each of said portions, each said tip being rotatable about a longitudinal axis thereof to provide a control for airflow between adjacent tips, means for independently or collectively rotating the tips of each series, said wing tips comprising flexible portions permitting yielding thereof to compensate for shocks acting thereon.

15. In a flying machine, wing portions on opposite sides thereof, a series of adjustable adjacent wing tips on each of said portions, said tips being supported on said portions to be extended therefrom in parallel relation to each other and means for independently or collectively extending the tips of each series.

16. In a flying machine, wing portions on opposite sides thereof, a series of adjustable adjacent wing tips on each of said portions, said tips being supported on said portions to be extended therefrom in parallel relation to each other, means for independently or collectively extending the tips of each series, and means for yieldably supporting said wing portions on said machine whereby to compensate for shocks.

17. In a flying machine, wings on opposite sides of said machine, means for selectively or collectively varying the area of said wings whereby to aid in banking or landing comprising a series of adjustable adjacent wing tips on each of said wings, the wing tips of each series being selectively or collectively movable to vary the airflow between the adjacent tips.

18. In a flying machine, wing portions extending laterally from opposite sides of said machine, a series of adjustably interconnected adjacent wedge shaped tip sections on each wing portion, and means for selectively or collectively moving certain of said sections to a position above the respective wing portion,

- and moving others of said sections to a position below the respective wing position.
19. In a flying machine, wings on opposite sides of said machine, each of said wings provided with a series of adjustable wing tips, a ball and socket joint support for each wing tip, means for independently or collectively controlling the tips of each series, said means comprising cams for rotating each tip about the respective joint. 5
20. In a flying machine, wings therefor, slots in said wings, a series of extensible wing extensions within said slots, control means within the wings and extending to an operator's position and comprising means for selectively or collectively varying the positions of said extensions with respect to said wings. 15
21. In a flying machine, wings therefor, slots in said wings, a series of extensible wing extensions within said slots, control means within the wings and extending to an operator's position, means for selectively or collectively varying the positions of said extensions with respect to said wings, and means 25 providing a yieldable cantilever attachment for said wing extension series.
22. In a flying machine, wings therefor, slots in said wings, a series of extensible wing extensions within said slots, control means within the wings and extending to an operator's position and comprising means for selectively or collectively varying the positions of said extensions with respect to said wings, each of said wing extensions comprising 30 flexible portions to compensate for wing shocks. 35
23. In a flying machine in combination, wings on opposite sides of said machine, a series of adjustable rotatable wing extensions on each of said wings, control means for selectively or collectively adjusting said extensions. 40
24. In a flying machine, opposite main planes therefor, each of said planes provided with a group of adjacent adjustable aerofoils, means for extending, retracting, and rotating the aerofoils of each group either selectively or collectively relative to the main plane whereby to vary the air stream 45 action on said aerofoils. 50
25. In a flying machine, a wing therefor, said wing comprising a main spar member, a plurality of adjacent layers of material on opposite sides of said spar and extending laterally thereof at uniformly increasing distances to provide a wing having its greatest strength adjacent said spar, the outermost of said layers being extended and connected at opposite ends to form wing edges. 55
26. In a flying machine, opposite main planes therefor, each plane provided with a series of adjacent adjustable wing tips, a control shaft, auxiliary levers pivoted on said shaft, means for selectively locking said levers to said shaft, a master lever secured 60 to said shaft, and control cables extending from said auxiliary levers to said tips whereby said tips may be selectively or collectively controlled within each series. 65
27. In a flying machine, wing portions on opposite sides of said machine, a series of adjustable, adjacent wing tips on each of said portions, each said tip being rotatable about a longitudinal axis thereof, and means for independently or collectively rotating the tips of each series, for relatively varying the effective area of said wing tips. 75
28. In a flying machine, opposite planes therefor, each plane provided with a series of adjustable wing tips, each said tip being movable as a unit around a vertical axis, a portion of each tip being rotatable around a horizontal axis, and means to move said tips or said portions. 80
29. In a flying machine, a wing therefor, said wing comprising a main spar member, a plurality of adjacent layers of material on opposite sides of said spar and extending laterally thereof at uniformly increasing distances to provide a wing having its greatest strength adjacent said spar, the outermost of said layers being extended and connected at opposite ends of form wing edges by being secured to a special strip into which they are fitted, said strip extending beyond the flanges. 85 90
30. In a flying machine, a wing therefor, said wing comprising a vertical web spar, laterally extending flanges for said spar, wing surfaces adjacent said flanges and extending oppositely from said spar to provide a wing surface, the outer edge of said flanges secured together by a connecting part into which they are mortised. 95
31. In a flying machine, opposite planes therefor, each plane provided with adjustable wing tips, each said tip being movable as a unit around a vertical axis, a portion of each tip being rotatable around a horizontal axis, and means to move said tips or said portions. 100
32. In a flying machine, opposite planes therefor, each plane provided with adjustable wing tips, each said tip being movable as a unit around a horizontal axis and means to move said tips to change the total span of wings under operating conditions. 110 115
